UNITED STATES PATENT OFFICE.

GEORGE J. MILLER, OF KANSAS CITY, MISSOURI.

BROILING APPARATUS.

No. 870,117.

Specification of Letters Patent.

Patented Nov. 5, 1907

Application filed September 29, 1906. Serial No. 336,764.

To all whom it may concern:

Be it known that I, GEORGE J. MILLER, a citizen of the United States of America, residing at Kansas City, in the county of Jackson and State of Missouri, have 5 invented certain new and useful Improvements in Broiling Apparatus; and I do hereby declare that the following is a full, clear, and exact description of the invention, such as will enable others to make and use the same, reference being had to the accompanying 10 drawings, forming a part of this specification.

The object of the invention primarily is an apparatus for broiling meats, poultry, etc., in which the meats to be broiled may be turned quickly when exposed to the fire and the juices thereby preserved. Second—The 15 turning of the broiler while being elevated in position above the heating grate. Third—To communicate a down draft to the smoke and vapor during the process of broiling. Fourth—To enable the attachment of any draft apparatus for forced draft.

20 The invention consists in the novel construction and combination of parts such as will be first fully described and then specifically pointed out in the claims.

In the drawings—Figure 1 is a view in perspective of the novel broiling apparatus, a portion of the case or frame being broken away to show the support for the inner ends of the removable ventilating and heating grate. Fig. 2 is a plan view of the apparatus with the broiler removed, the heating grate being broken away to show the lower chamber and the aperture and cover 25 in the bottom of the chamber. Fig. 3 is a transverse vertical sectional view of the apparatus as seen in Fig. 1. Fig. 4 is an end view of the upper portion of the frame showing the broiler supporting frame and the broiler rotating devices in an upwardly extended position. Fig. 5 is a detail side view enlarged of one of the outer jointed bars connected with the broiler showing the ratchet teeth in the jaw or yoke. Fig. 6 is a plan view of the jaw or yoke showing the ratchet teeth. Fig. 7 is a detail side-view of the separable supporting 30 plates for the trunnions of the broiler on the broiler supporting frame. Fig. 8 is a transverse sectional view enlarged of the trunnion showing the ratchet teeth thereon. Fig. 9 is a detail view of the adjusting bolt and nut for the jointed arms. Fig. 10 and 10^X are 35 views of the outer jointed bar connected with the broiler as seen in Fig. 5 and 6 without the ratchet teeth. Fig. 11 is a modified view in perspective of the broiler raising and lowering and turning devices, the lower portion of the case or frame being broken away. Fig. 40 40 12 is a view of a modification of the broiler.

Similar numerals of reference indicate corresponding parts in all the figures of the drawing.

Referring to the drawings 20 indicates a rectangular shaped case or frame composed of the sides 21, 21^X, 22, 45 22^X and bottom 23, preferably constructed of thin metal. In the end 22, 22^X of the case at points equi-

distant from the sides 21, 21^X and extending a short distance downwardly from the upper horizontal surfaces of said ends are oblong openings or slots 24, the lower surfaces of which openings are curved in the arc 60 of a circle.

Upon the inner surfaces and ends of the case or frame are secured the horizontal broiler supporting flanges 25 which extend from the inner surfaces of one side of the box to the inner surfaces of the other side and a 65 slight distance below the line of the lower curved surfaces of the openings or slots 24.

Upon the inner surfaces of the ends 21, 21^X at points equi distant from the upper and lower horizontal surfaces of the box are horizontal flanges 26 of the same 70 length as the flanges 25, the flanges upon one end 21^X of the box being short in length as further described. The flanges 26 support a ventilating and fuel burning grate 27 extending transversely to the box and beneath which grate is a chamber 28 for smoke and vapor arising 75 from the broiling of the meats or other food. In the side 21^X of the box is an opening or flue 29 leading from the chamber 28 and upon the outer surface of said side extending around said opening is an annular flange or collar 30 and in which collar as shown is fitted a flanged 80 cover 31. The fuel burning and ventilating grate 27 consists of pipes or burners 32 perforated at 32^X upon their upper surfaces, said pipes extending from the inner surface of one end 22^X nearly to the inner surface of the other end 22 and closed by suitable plugs 33 at 85 each end. A series of pipes or burners 32 are employed extending parallel with each other. In the end 22^X of the box opposite the ends of the pipes or burner 32 are openings 35 through which extend the nipples 36 which are smaller in circumference than the pipes 32, 90 the inner ends of which nipples extend through the plugs 33 a short distance within the pipes 32 and support said pipes detachably in position. Extending in the longitudinal direction of the pipes 32 and laterally from the opposite surfaces and in the line of the diameter of said pipes are short flanges 37 and from the outer surfaces of the flanges extend the plates or webs 38, which plates are curved in the arc of a circle and the upper ends of which plates extend a short distance above the line of the horizontal upper surfaces of the 100 said pipes and to a position a short distance from a vertical line extending through said grate equi distant from said pipes thus forming between the outer longitudinal surfaces of adjacent parallel plates 38 the longitudinal slots or ventilating openings 39. Upon the 105 ends of the plates 38 of the box are lugs 40 which rest upon the flanges 26.

The portions of the grate adjacent to the inner surface of the side 21 of the box consist of narrow plates 41, supported upon the flanges 26, at one end and the end 110 21 of the box and also upon the short flanges 26 upon the end 22^X of the box. In width these plates 41 ex-

tend from the inner surfaces of the sides of the box to within a short distance of the longitudinal outer surfaces of the plates 38 thus leaving a slot or opening of the same width as the slot or opening 39 between the 5 surfaces of adjacent plates. Upon the outer ends of the nipples 36 are internally screw threaded caps 45, in which are ordinary cut off valves and with which valves are connected the valve stems 47 which extend through the said caps 45 and upon the outer ends of 10 said stems are wheels or handles 48. With the lower surfaces of the sides of the caps 45 are connected the upper ends of short pipes 49 and with the lower end of one of said pipes is connected an elbow 50 and with the other pipes the three way pipe connections 51 the 15 elbow and one of said connections being connected by means of a short length of pipes 52, the other connections 51 being connected by a short length of pipe 53. 54 indicates a gas supply pipe for gaseous fuel and is connected with the source of supply at one end and 20 with one of the three way connections 51 at the other end.

In the bottom 23 of the box is a large circular opening 42 in the sides of which opening is fitted the annular flange 43 upon the inner surface of the cover 44, 25 which cover is larger than said opening and closes upon the outer surface of the bottom 23 of said box.

55 indicates the broiler which consists of two frames between which the meat is placed for the purpose of broiling or roasting, the details of construction of which 30 broiler will be made the subject matter of a separate application. For the purpose of illustration it will be observed that the separate frames of the broiler comprise series of cross wires 55^X upon which the articles are laid and that the frames are mounted on the trunnions 35 56, the outer portions of the frames extending to within a short distance of the inner surfaces of the sides 21 of the box the lower frame resting upon the flanges 25 within the case and the outer ends of the trunnions extend through the slots 24 in the ends 22, 22^X of the 40 case. Upon said outer end portions of the trunnions are wheels or handles 57. The frames may be kept closed by a wire and hook 54°. 58 indicates the device or lever for raising and lowering the broiler which consists of the rocking bar 59 and 60 arranged in position 45 near the upper portions of the sides 21 and 21^X of the case and a short distance from the outer surfaces of the case. The ends of these bars extend a slight distance beyond the line of the ends 22, 22^X of the case. The bar 59 is connected with the outer leaves of inverted 50 hinges 61 arranged near the upper surface of the case, the inner leaves being secured rigidly to the case. With the outer ends of the bars 59 and 60 are connected rigidly the lever arm 62 which extends parallel with the outer surface of the ends 22, 22^X of the case and are bent 55 in a downwardly curved line from the bars 59 and 60 and below the line of the bottom of the slots 24 in the ends 22, 22^X of the case and also bent at both ends a slight degree inwardly. Connected rigidly with the upper surfaces of the curved lever arms 62 opposite 60 the slots 24 are upwardly extended plates 63 in which are annular openings or bearings 65 for the trunnions 56, supporting the broiler 55 in the upper portions of which plates are slots or openings 66, leading to the bearings or openings 65 which slots permit the passage 65 of the trunnions. The trunnion supports or plates 63

as shown are made in two parts and riveted to the outer surfaces of the lever arms.

Upon the portion of the trunnions 56 extending beyond the flange 67 are ratchet teeth 68 as seen in cross section in Fig. 8, these teeth being made to extend in the opposite direction to the direction of rotation of the trunnions 56. Upon the ends 22, 22^X of the box and extending at an angle to and located a short distance from the sides of the slots 24 toward the side 21 of the case are the longitudinally grooved plates in which is a sliding pivot bolt 70 having a square shoulder 70^X. Upon said bolt is a sleeve 70° having a shoulder 70^{XX}. Upon the bolt 70 is a thumb screw 69*. The lower end of a bar 71 fits over the sleeve 70° on the bolt 70. The other end of said bar extends upwardly a short distance 80 and with which end is pivotally connected at 72, the lower end of a short bar 73. Upon the upper end of the bar 73 is connected rigidly one side portion of a U shaped trunnion grasping yoke or jaw 74, extending inwardly beyond the line of the lower surface of the bar 73 and consisting of a plate bent in the arc of a circle and extended about two thirds the distance in the direction of the line of the circumference of the trunnion 56, a portion 74 of which U shaped portion extends laterally and inwardly and upon the inner surface of which jaws 85 are ratchet teeth engaging with the ratchet teeth 68 upon the said trunnions. In the outer curved surface of the plate 74 is a groove 74^X which receives the flange 67. The sides of the opening 76 in plate 75 leading to the ratchet teeth are the proper distance apart to register with the opening 66 in plate 63 for the entrance of the trunnions 56, the connection of the plate 74 being made with the plate 63 when the separate parts are united with the bar 62. When the trunnions are introduced within the openings 66 and 76 the ratchet teeth 75 in plate 74, the broiler resting upon the flanges 25 in the case. Upon the outer free end of one of the bars 62 supporting the trunnion 56 is a handle 77.

In the side 21 of the case to which the bar 59 is 105 hinged and at a point equi distant from the line of the ends 22, 22^X of the case is a vertical slot 78 which extends from a point a short distance below a line parallel with the under surface of the bar 59 and downwardly to a point above a line extending horizontally 110 through the flanges 25. Upon the outer surface of the side 21 of the case below the lower end of the slot is rigidly connected the lower end of a spring plate 79, the upper end of which plate is bent inwardly within the slot 78, then bent at an angle to itself and extended 115 upwardly and outwardly from the upper portion of said slot forming a V shaped hook or spring catch 80 the position of which is just above one side of the lower frame of the broiler as seen in Fig. 3.

In the employment of the broiling apparatus the 120 cover 31 is removed from the flue opening 29 and the flange 30 connected with a pipe leading to an open fire place or chimney or other exit or draft opening for smoke. Gas is admitted to the burners 32 by opening the valves 48. These burners 32 are larger than the 125 nipples 46 thus adapting the apparatus to the use of either natural or artificial hydro carbon gas which is admitted through the conducting pipe 54. In the employment of the former gas the grate 27 upon each side of the longitudinal slots 39 may be covered with broken 130

- terra cotta or fire proof material which will absorb heat and radiate the same under low fire and the fire tempered so that the roasting may be gradual without liability of burning the gas permeating the material.
- 5 During the roasting the draft upon the opening 29 acts to cause a down draft of the smoke and vapor and also of the unconsumed gas which passes through the openings 39, into the chamber 28 and thence out of the chamber through the said opening and preventing the smoke and odors from entering the room and also preventing the deleterious action of gas on the meats. If preferred the cover 44 may be removed from the opening 42 in the bottom 23 of the case and the case placed upon the stove or range, from which the cover has been
- 10 removed and the opening 42 caused to register with the opening in the range thus utilizing the natural draft of the stove or range to carry off the smoke. The drippings from the meat in broiling which will escape in some degree before the meat is seared will fall upon the flanges 38, the apertures 39 being above the horizontal plane of the burner so that the down draft will not be impeded by clogging of the apertures. The drippings which fall upon the flanges are conducted to the upper surface of the flanges 37 in the heat of the burner and are carbonized the smoke passing through the apertures 39.
- In order to raise the broiler from the supporting flanges 25 power is applied to the handle 77 and the frame 58 is raised upon its hinges 61 and at the same time an initial start toward rotation of the broiler frames 55 is imparted by the spring hook 80 and the pivoted bars 71 and 73 are extended, the jaws simultaneously maintaining a rigid grasp upon the trunnions 56 of the broiler and causing rotary movement to be imparted to said frame and upon the completion of the upward movement of the supporting lever arms 62 the bars 71 and 73 are in line with each other the U shaped jaw 74 being in a reversed position with the opening 76, turned past the opening 66 in the bearing 63 and 40 in a downward direction, thus locking the trunnions and the broiler frames in the meantime being also in a reversed position for exposing other portions of the meat to the fire the position of the jaw 74 being such as to prevent the dislodgement of the trunnions from the 45 raising and lowering frame and the U shaped journal bearings 63. When the broiler is lowered in position the openings 66 on the journal bearing and the openings 76 to the jaws 74 register with each other and in which position the trunnions on the broiler may be raised out 50 of the said openings. In lowering the frame 58 with the broiler the ratchet 75 upon plate 74 and the ratchet teeth 68 on the trunnions 56 slip past each other and the broiler frame moves downwardly to the position for roasting as before. The lever arms 62 rest at all 55 times upon the pivot bolt 70 and may be raised and lowered to adjust the height of the bar 71 to the height necessitated by the trunnions 56 by thumb screw 70X.
- Instead of frame 58 for raising and lowering the broiler I may employ the modified construction as seen 60 in Fig. 11. The case 81 as seen in said figure is substantially the same as in Fig. 1. The spring hook 84 is the same as the spring hook 80 in Fig. 1. The modification of the frame 58 consists of a rod 85 which extends parallel with the outer surface and upper end of 65 the side 82 above the slot 84X in the said side for said
- spring catch 84. This rod extends a short distance beyond the ends 83 of the case and is fulcrumed or journaled in the brackets 86 which are connected with the said ends 83 of the case the upper ends of the bracket being inclined a slight distance outwardly and beyond. 70 the upper outwardly inclined portion of the sides 82 of the case. The ends of the rod 85 are bent at right angles to form lever arms and extended to a position opposite the openings 87 in the ends of the case which openings are the same as the openings 24 in Fig. 1. Said ends 75 of the rods are bent upwardly and extended rearwardly a short distance in the arc of a circle as at 88. Upon the upper surface of the said ends of the rods adjacent to the bent portion 88 are ratchet teeth 89. The trunnions 90 of the broiler are held between spring clips 91 80 consisting of a plate extending in an arc of a circle on the lower surfaces of the ends of rod 85 and thence bent inwardly a short distance toward each other to form a loose sleeve and the ends of the plate bent outwardly in the arc of a circle to receive and clasp the trunnions 90. 85 Upon the trunnions are ratchet teeth 92 as in Fig. 1 which engage with the ratchet teeth upon the ends of the lever arms on rods 85. Upon the rod 85 is a short arm 93 upon which is a detachable handle 94. Connected pivotally at one end with the portion of the 90 clips 91 on the ends of lever arms on rod 85 are rods 95 the other ends of which rods are extended forwardly and connected pivotally with the ends 83 of the case near the parallel side 82X of the case. The broiler is raised repeatedly in this modification by the power 95 applied to the handle or arm 94 in which movement the clip 91 supporting the trunnions 90 move in opposite directions, the teeth upon the rod obtaining a grasp upon the ratchet teeth upon the trunnions 90 in each forward movement of the clips and imparting rotation 100 to the trunnions 90, the bending of the upper portions of the sides of the box outwardly affords space for the movement of the frame of the broiler. In the repeated movements upwardly and downwardly of the broiler frame the portion of the frame toward the side 82 comes 105 into contact with the spring plate 84 and upper surface of the hooks obtaining in each impact an initial movement upwardly to assist the rotation of the trunnions by the ratchet teeth.
- The ratchet teeth upon the jaw 74 as in Fig. 1 may 110 be dispensed with if desired and the surface left smooth as seen in Figs. 10 and 10X. In this construction the jaw 96 will obtain a fractional grasp upon the trunnions which as shown in Fig. 9 in section will be made with corresponding frictional surfaces.
- It is obvious that instead of the broiler frames as shown an ordinary spit may be employed of which the trunnions will form an integral part as seen in Fig. 12 in which 97 is the spit 98 the trunnions rotation being imparted to the spit as the spit is raised in position in 120 corresponding manner with the rotation of the broiler frames. The spring plate 79 may be dispensed with and such other modifications employed as are within the scope of the invention.
- Having fully described my invention what I now 125 claim as new and desire to secure by Letters Patent is—
1. In a broiling apparatus the combination with the case of a broiler a rocking bar journaled on said case lever arms upon said rocking bar means for rocking said bar and suitable bearings upon the lever arms for the broiler. 130

2. In a broiling apparatus the combination with the case and with a rotary broiler and trunnions upon said broiler of a rocking bar journaled on said case lever arms upon said rocking bar, means for rocking said bar and bearings 5 on the lever arms supporting the trunnions on the broiler.
3. In a broiling apparatus the combination with the case and with a rotary broiler and trunnions upon said broiler of a rocking bar journaled upon said case, means for rocking said bar, lever arms upon said rocking bar and journal 10 bearings having openings for the trunnions upon the said lever arms and rotary securing devices upon the journal bearings for securing the trunnions removably within said bearing.
4. In a broiling apparatus a case, a broiler and perforate pipes or burners within said case beneath the broiler, longitudinally extended flanges extending from the opposite sides of said pipes and lateral extensions of said flanges extending in an upward direction above the horizontal plane of the burners, the said flanges upon the 15 respective pipe burners being inclined toward each other and having apertures between for the down draft of the smoke.
5. The combination in a broiling apparatus with a supporting frame of a rock bar journaled thereon, lever arms connected with the rock bar, a rotary broiler trunnions upon said broiler suitable journal bearings on the lever arms for said trunnions, inner and outer jointed bars pivotally connected with said supporting frame and yokes on the outer ends of said outer bars grasping said trunnions and means 20 for operating the rocking bar.
6. In a broiling apparatus the combination with the supporting frame and the broiler and with the trunnions supporting said broiler raising and lowering devices for said broiler and journal bearings thereon having separate 25 grasping parts and a rotary annular yoke grasping said trunnions having a grooved outer surface adapted to receive the separate parts of the journal bearings and a bar for operating said yoke.
7. In a broiling apparatus the combination with a suitable case lever arms fulcrumed thereon, a broiler trunnions 30 on said broiler journaled upon said arms, ratchet teeth on said trunnions extensible inner and outer jointed bars said inner bars being pivotally connected with said case, yokes on said outer bars and ratchet teeth in said yokes engaging with the ratchet teeth upon said trunnions.
8. In a broiling apparatus the combination with a suitable case, a broiler, trunnions on said broiler, lever arms fulcrumed on said case, supporting devices upon said arms for said trunnions, means for locking said trunnions on 35 said supports when the lever arms are raised in position, rods or bars pivotally connected with said case and means on said bars and said trunnions for imparting a rotary movement to said trunnions and means for adjusting the
- position of said trunnions supporting devices to the changed positions of the trunnions. 55
9. In a broiling apparatus the combination with a suitable case, lever arms fulcrumed upon said case and journal boxes upon said arms having separable parts a broiler trunnions on said broiler and ratchet teeth on said trunnions extensible jointed bars pivotally connected with each other and said case, yokes on said bars rotatively connected with said journal boxes and ratchet teeth on said yokes engaging with the ratchet teeth on said trunnions. 60
10. In a broiling apparatus the combination with a suitable case, a broiler, trunnions on said broiler and ratchet teeth on said trunnions, lever arms fulcrumed on said case, journal bearings upon said arms jointed arms pivotally connected with said case and yokes on said arms having extensible grooved portions within said journal bearings and rotatively fitted thereto, said yokes being adapted to admit the trunnions to its center and ratchet teeth upon the inner circular portion of said yokes engaging with the ratchet teeth on said trunnions. 65
11. In a broiling apparatus the combination with a suitable case of lever arms fulcrumed on said case journal boxes upon said lever arms, a broiler, trunnions thereon journaled in said boxes, arms on said case and grasping jaws on said arms imparting a rotary movement to said arms. 70
12. In a broiling apparatus the combination with a suitable case lever arms fulcrumed thereon, journal bearings upon said lever arms, extensible bars pivotally connected with each other and said case grasping jaws upon said extensible bars adapted to grasp said trunnions and laterally extended portions of said jaws having externally grooved surfaces within the said journal bearings. 75
13. In a broiling apparatus the combination with a suitable case, lever arms fulcrumed on said case, journal boxes on said lever arms, a broiler trunnion thereon journaled in said boxes, jointed inner and outer arms on said case grasping arms on the outer arms imparting a rotary movement to said trunnions and adjusting devices on said case with which the inner arms are pivotally connected. 80
14. In a broiling apparatus the combination with a suitable case and with lever arms fulcrumed on said case and suitable journal bearings and trunnions supporting said frame within said bearings upon the lever arms, devices on said lever arms connected with the trunnions acting to impart a rotary movement to said broiler frame and a spring actuated plate on the said case with which the said broiler frame comes in contact. 85
